CONCRETE BUILDING CONSTRUCTION

Heriberto Amescua, Laredo, Tex.

Application November 13, 1935, Serial No. 49,608

17 Claims. (Cl. 72—1)

The invention relates to a concrete building construction and more especially to a system of building construction using precast concrete units.

- 5 The primary object of the invention is the provision of a building construction of this character, wherein through the use of precast concrete units, these being in the form of slabs which by their shape and dimension under assembly form 10 walls and roofs with air spaces and at the same time permit placement of reinforcing steel either plain or fabricated and the pouring of concrete to provide a continuously reinforced structure of any height and involving one or more stories.
- 15 Another object of the invention is the provision of a building construction of this character, wherein through the use of the precast units economy of material is assured and likewise labor, quickness of erection, fireproof and having a very low cost of maintenance, permitting the easy 20 placement of a wall finish like Celotex, sheet rock or similar material as a furring may be placed between the units and such material as just mentioned nailed thereon.
- 25 A further object of the invention is the provision of a building construction of this character, wherein a monolithic reinforced edifice is attained with a continuity of arrangement and with a thickness to such edifice in its walls and floors 30 for sustaining loads or weights and in the erection eliminates any necessity for alteration in the slabs or units as to the shape, weight and volume thereof.

A still further object of the invention is the provision of a building construction of this character, wherein monolithic characteristics thereof with a continued succession in erection and in the use of precast units or slabs, these in the assembly 35 allow cavities for casting structural columns in the corners or unions of walls in their various distribution and such erection does not require skilled labor as the units or slabs can be quickly brought to place without much trouble and without using timber props at all.

40 A still further object of the invention is the provision of a building construction of this character, wherein there is involved refinements, over the subject matter of United States Letters Patent No. 2,001,696 issued May 21, 1935, the construction being reinforced and susceptible of 45 withstanding weather changes, possessed of strength and durability and inexpensive to erect.

With these and other objects in view, the invention consists in the features of construction, combination and arrangement of parts as will be

hereinafter more fully described, illustrated in the accompanying drawings, which disclose the preferred embodiment of the invention and pointed out in the claims hereunto appended.

In the accompanying drawings:

Figure 1 is a fragmentary perspective view of a concrete construction in accordance with the invention.

Figure 2 is a view similar to Figure 1 looking from the outside of the structure.

Figure 3 is a fragmentary perspective view of one of the slabs or units.

Figure 4 is a fragmentary enlarged horizontal sectional view through one of the walls of the structure.

Figure 5 is an edge view of a ceiling slab.

Figure 6 is a fragmentary elevation at one of the joints of a vertical wall of the structure.

Figure 7 is a horizontal sectional view through one of the columns of the structure.

Figure 8 is a view similar to Figure 7 through another of the columns or the corner column.

Similar reference characters indicate corresponding parts throughout the several views in the drawings.

Referring to the drawings in detail, the reinforced concrete construction comprises a foundation including the required number of precast horizontally arranged blocks 10 which when end to end serve as beams or sills and are leveled and supported directly on the ground or by means of a sub-base of any adequate material and the same may be rod reinforced. These sills or beams are joined in any suitable manner and being arranged with relation to each other according to the desired framing of an edifice.

Formed in the upper faces of the blocks 10 are channels or grooves 11, the sides 12 being disposed in upwardly divergent relation to each other and into these channels or grooves 11 are fitted the lower ends of precast slabs or units 13 and 14, respectively, the latter forming the inside wall while the former the outside wall of the edifice. These slabs or units 13 and 14 are similar to each other and have formed at their innermost faces substantially rectangular frame-like flanges 15 with reversely beveled or angled faces 16 and 17, respectively, the flange 15 on each slab at one end of the latter being removed from that end next thereto to provide a beam recess 18.

These slabs 13 and 14 are arranged side by side with the flanges 15 confronting each other, the latter being joined by a plastic bonding 19 and thus there is provided between said slabs an air chamber or space 20. The inner faces of the 55

slabs 13 and 14 are formed with the longitudinal and transverse brace ribs 21 within the frame-like flanges 15 while embedded in said slabs are longitudinal and transversely disposed reinforcing rods 22 and 23, respectively.

At a corner of an edifice and at a dividing wall as may be provided therein the slabs 13 and 14 in association with corner angle precast concrete pieces 24 and outside facing pieces 25, respectively, effect spaces for the pouring of cementitious or concrete columns 26 and 27, respectively, these having embedded therein rod reinforcements 28, the reinforcements 28 extending longitudinally of such columns being extended into the sills or beams constituting the foundation 10 and such beams fit the reversely beveled sides 16 of the slabs 13 and 14 as is clearly shown in Figures 7 and 8 of the drawings.

The flanges 15 at the longitudinal sides of the slabs 13 and 14 are provided with holes or passages 29 for accommodating tie or anchoring elements 30, these being set in fillings 31 poured between the reversely beveled faces 16 of the side edges of said slabs 13 and 14 as is clearly shown in Figure 4 of the drawings and such elements are loose within the passages or holes 29 so as to allow for expansion and contraction of the walls of the edifice according to the changes of weather elements.

The flanges 15 at the longitudinal sides of said slabs 13 and 14 have embedded therein rod reinforcements 32 which extend into the recesses 18 and into these recesses is poured cementitious material or concrete to provide horizontal beams 33, the latter also being provided with metallic reinforcements 34.

Corelated with the walls constituted by the slabs 13 and 14 are the precast concrete ceiling and floor slabs 35 and 36, respectively. The ceiling slabs 35 have the intermediate and outer ribs 37 and 38, respectively, with reversely angled sides 39 while the floor slabs have the angled side flanges 40 longitudinally thereof and poured between the slabs 35 and 36, these being set edge to edge, is cementitious or concrete filling 41, the said slabs 35 and 36 being provided with metallic reinforcements 42 which are embedded therein and are arranged transversely and longitudinally of the same.

The slabs 13 and 14 in their vertical disposition to constitute the walls, both outside and dividing walls, are joined with the sills in the grooves or channels 11 with cementitious fillings 43 located between the sides 12 and the outer faces of said slabs 13 and 14, respectively.

The fillings 31 carry reinforcing rods 44 which may continue throughout such fillings in a vertical direction between the inner and outer slabs 13 and 14.

Under the construction described there is obtained a truly monolithic edifice of fully reinforced concrete, the reinforcements of which is continuous notwithstanding the fact that there is used the precast slabs or units in the erection of the edifice. The embedded reinforcements in the respective fillings and beams will project into the columns and thus the entire edifice is unitary, the slabs 36 being also serviceable as roofing.

What is claimed is:

1. In a building construction of the kind described, a precast concrete foundation having channeled upper sides, precast concrete inner and outer wall slabs fitting the channeled upper side of said foundation and having inner surface formations matching each other to form air spaces

between said slabs, fillings between the edges adjacent to each other of said slabs and anchoring elements loosely fitting said slabs and embedded in said fillings.

2. In a building construction of the kind described, a precast concrete foundation having channeled upper sides, precast concrete inner and outer wall slabs fitting the channeled upper side of said foundation and having inner surface formations matching each other to form air spaces between said slabs, fillings between the edges adjacent to each other of said slabs and anchoring elements loosely fitting said slabs and embedded in said fillings, the edges next to each other of the slabs being reversely beveled and confronting said fillings.

3. In a building construction of the kind described, a precast concrete foundation having channeled upper sides, precast concrete inner and outer wall slabs fitting the channeled upper side of said foundation and having inner surface formations matching each other to form air spaces between said slabs, fillings between the edges adjacent to each other of said slabs, anchoring elements loosely fitting said slabs and embedded in said fillings, the edges next to each other of the slabs being reversely beveled and confronting said fillings, angled corner pieces associated with said slabs and poured concrete columns between the angled pieces and the edges adjacent thereto of said slabs.

4. In a building construction of the kind described, a precast concrete foundation having channeled upper sides, precast concrete inner and outer wall slabs fitting the channeled upper side of said foundation and having inner surface formations matching each other to form air spaces between said slabs, fillings between the edges adjacent to each other of said slabs, anchoring elements loosely fitting said slabs and embedded in said fillings, the edges next to each other of the slabs being reversely beveled and confronting said fillings, angled corner pieces associated with said slabs, poured concrete columns between the angled pieces and the edges adjacent thereto of said slabs, the slabs being formed with horizontal beam recesses and poured concrete beams filling said recesses.

5. In a building construction of the kind described, a precast concrete foundation having channeled upper sides, precast concrete inner and outer wall slabs fitting the channeled upper side of said foundation and having inner surface formations matching each other to form air spaces between said slabs, fillings between the edges adjacent to each other of said slabs, anchoring elements loosely fitting said slabs and embedded in said fillings, the edges next to each other of the slabs being reversely beveled and confronting said fillings, angled corner pieces associated with said slabs, poured concrete columns between the angled pieces and the edges adjacent thereto of said slabs, the slabs being formed with horizontal beam recesses, poured concrete beams filling said recesses and metallic reinforcements in the slabs, columns and beams.

6. In a building construction of the kind described, a precast concrete foundation having channeled upper sides, precast concrete inner and outer wall slabs fitting the channeled upper side of said foundation and having inner surface formations matching each other to form air spaces between said slabs, fillings between the edges adjacent to each other of said slabs, anchoring elements loosely fitting said slabs and embedded

75 70 60 55 50 45 40 35 30 25 20 15 10 5

in said fillings, the edges next to each other of the slabs being reversely beveled and confronting said fillings, angled corner pieces associated with said slabs, poured concrete columns between the 5 angled pieces and the edges adjacent thereto of said slabs, the slabs being formed with horizontal beam recesses, poured concrete beams filling said recesses, metallic reinforcements in the slabs, columns and beams and ceiling and floor slabs associated with said first-mentioned slabs and beams.

7. In a building construction of the kind described, a precast concrete foundation having channeled upper sides, precast concrete inner and outer wall slabs fitting the channeled upper side 15 of said foundation and having inner surface formations matching each other to form air spaces between said slabs, fillings between the edges adjacent to each other of said slabs, anchoring elements loosely fitting said slabs and embedded 20 in said fillings, the edges next to each other of the slabs being reversely beveled and confronting said fillings, angled corner pieces associated with said slabs, poured concrete columns between the angled pieces and the edges adjacent thereto of 25 said slabs, the slabs being formed with horizontal beam recesses, poured concrete beams filling said recesses, metallic reinforcements in the slabs, columns and beams, ceiling and floor slabs associated with said first-mentioned slabs and beams and 30 fillings between said last-mentioned slabs.

8. In a building construction of the kind described, a precast concrete foundation having channeled upper sides, precast concrete inner and outer wall slabs fitting the channeled upper side 35 of said foundation and having inner surface formations matching each other to form air spaces between said slabs, fillings between the edges adjacent to each other of said slabs, anchoring elements loosely fitting said slabs and embedded 40 in said fillings, the edges next to each other of the slabs being reversely beveled and confronting said fillings, angled corner pieces associated with said slabs, poured concrete columns between the angled pieces and the edges adjacent 45 thereto of said slabs, the slabs being formed with horizontal beam recesses, poured concrete beams filling said recesses, metallic reinforcements in the slabs, columns and beams, ceiling and floor slabs associated with said first-mentioned slabs 50 and beams, fillings between said last-mentioned slabs and rib formations on the last-mentioned slabs and confronting each other to form spaces therebetween.

9. In a building construction of the kind described, a precast concrete foundation having channeled upper sides, precast concrete inner and outer wall slabs fitting the channeled upper side 55 of said foundation and having inner surface formations matching each other to form air spaces between said slabs, fillings between the edges adjacent to each other of said slabs, anchoring elements loosely fitting said slabs and embedded in said fillings, the edges next to each other of the slabs being reversely beveled and confronting said 60 fillings, angled corner pieces associated with said slabs, poured concrete columns between the angled pieces and the edges adjacent thereto of said slabs, the slabs being formed with horizontal beam recesses, poured concrete beams filling said 65 recesses, metallic reinforcements in the slabs, columns and beams, ceiling and floor slabs associated with said first-mentioned slabs and beams, fillings between said last-mentioned slabs, rib formations on the last-mentioned slabs and 70 confronting each other to form spaces therebetween.

and fillings joining the first-mentioned slabs with the foundation.

10. In a building construction of the kind described, a precast concrete foundation having channeled upper sides, precast concrete inner and outer wall slabs fitting the channeled upper side 5 of said foundation and having inner surface formations matching each other to form air spaces between said slabs, fillings between the edges adjacent to each other of said slabs, anchoring 10 elements loosely fitting said slabs and embedded in said fillings, the edges next to each other of the slabs being reversely beveled and confronting said fillings, angled corner pieces associated with said slabs, poured concrete columns between the angled pieces and the edges adjacent thereto of said slabs, the slabs being formed with horizontal beam recesses, poured concrete beams filling said recesses, metallic reinforcements in the slabs, columns and beams, ceiling and floor 20 slabs associated with said first-mentioned slabs and beams, fillings between said last-mentioned slabs, rib formations on the last-mentioned slabs and confronting each other to form spaces therebetween, fillings joining the first-mentioned slabs 25 with the foundation and reinforcements embedded in the fillings between the edges adjacent to each other of the first-mentioned slabs.

11. A construction of the character described comprising a precast foundation, opposed vertical 30 precast slabs seated in the foundation edge to edge and spaced from each other to form a hollow wall, matched marginal projections on the slabs and meeting each other to provide dead air 35 spaces in the hollow wall, the faces of the projections at the meeting edges of the opposed slabs being reversely beveled to provide columnar filling spaces therebetween, and poured cement fillings within said spaces and interlocked with the projections for effecting sealing joints between the slabs and between the dead air spaces.

12. A construction of the character described comprising a precast foundation, opposed vertical precast slabs seated in the foundation edge 45 to edge and spaced from each other to form a hollow wall, matched marginal projections on the slabs and meeting each other to provide dead air spaces in the hollow wall, the faces of the projections at the meeting edges of the opposed slabs being reversely beveled to provide columnar 50 filling spaces therebetween, poured cement fillings within said spaces and interlocked with the projections for effecting sealing joints between the slabs and between the dead air spaces, and anchoring elements fitting the projections of 55 opposed slabs for connecting together the said opposed slabs.

13. A construction of the character described comprising a precast foundation, opposed vertical precast slabs seated in the foundation edge 60 to edge and spaced from each other to form a hollow wall, matched marginal projections on the slabs and meeting each other to provide dead air spaces in the hollow wall, the faces of the projections at the meeting edges of the opposed 65 slabs being reversely beveled to provide columnar filling spaces therebetween, poured cement fillings within said spaces and interlocked with the projections for effecting sealing joints between the slabs and between the dead air spaces, and anchoring elements fitting the projections of 70 opposed slabs for connecting together the said opposed slabs and embedded in the fillings.

14. A construction of the character described comprising a precast foundation, opposed vertical 75

- 5 precast slabs seated in the foundation edge to edge and spaced from each other to form a hollow wall, matched marginal projections on the slabs and meeting each other to provide dead air spaces in the hollow wall, the faces of the projections at the meeting edges of the opposed slabs being reversely beveled to provide columnar filling spaces therebetween, poured cement fillings within said spaces and interlocked with the 10 projections for effecting sealing joints between the slabs and between the dead air spaces, anchoring elements fitting the projections of opposed slabs for connecting together the said opposed slabs and embedded in the fillings, and 15 metallic reinforcements embedded in said slabs.
15. A construction of the character described comprising a precast foundation, opposed vertical precast slabs seated in the foundation edge to edge and spaced from each other to form a hollow wall, matched marginal projections on the slabs and meeting each other to provide dead air 20 spaces in the hollow wall, the faces of the projections at the meeting edges of the opposed slabs being reversely beveled to provide columnar filling spaces therebetween, poured cement fillings within said spaces and interlocked with the 25 projections for effecting sealing joints between the slabs and between the dead air spaces, anchoring elements fitting the projections of opposed slabs for connecting together the said opposed slabs and embedded in the fillings, metallic reinforcements embedded in said slabs, and metallic reinforcements in said fillings.
16. A construction of the character described 30 comprising a precast foundation, opposed vertical precast slabs seated in the foundation edge to edge and spaced from each other to form a hollow wall, matched marginal projections on the slabs and meeting each other to provide dead air 35 spaces in the hollow wall, the faces of the projections at the meeting edges of the opposed slabs being reversely beveled to provide columnar filling spaces therebetween, poured cement fillings within said spaces and interlocked with the 40 projections for effecting sealing joints between the slabs and between the dead air spaces, anchoring elements fitting the projections of opposed slabs for connecting together the said opposed slabs and embedded in the fillings, metallic reinforcements embedded in said slabs, metallic reinforcements in said fillings, precast facing pieces seated by the fillings for closing the joints between the slabs at the outer faces of the latter, the slabs being formed with horizontal beam 45 recesses, and poured concrete beams filling said recesses.

spaces in the hollow wall, the faces of the projections at the meeting edges of the opposed slabs being reversely beveled to provide columnar filling spaces therebetween, poured cement fillings within said spaces and interlocked with the projections for effecting sealing joints between the slabs and between the dead air spaces, anchoring elements fitting the projections of opposed slabs for connecting together the said opposed slabs and embedded in the fillings, metallic reinforcements embedded in said slabs, metallic reinforcements in said fillings, and precast facing pieces seated by the fillings for closing the joints between the slabs at the outer faces of the latter.

17. A construction of the character described 15 comprising a precast foundation, opposed vertical precast slabs seated in the foundation edge to edge and spaced from each other to form a hollow wall, matched marginal projections on the slabs and meeting each other to provide dead air 20 spaces in the hollow wall, the faces of the projections at the meeting edges of the opposed slabs being reversely beveled to provide columnar filling spaces therebetween, poured cement fillings within said spaces and interlocked with the 25 projections for effecting sealing joints between the slabs and between the dead air spaces, anchoring elements fitting the projections of opposed slabs for connecting together the said opposed slabs and embedded in the fillings, metallic 30 reinforcements embedded in said slabs, metallic reinforcements in said fillings, precast facing pieces seated by the fillings for closing the joints between the slabs at the outer faces of the latter, the slabs being formed with horizontal beam 35 recesses, and poured concrete beams filling said recesses.
